UNITED STATES PATENT OFFICE.

WILLIAM M. BARBER, OF SOMERVILLE, MASSACHUSETTS.

MACHINE FOR DRYING PAPER.

1,261,343.

Specification of Letters Patent. Patented Apr. 2, 1918.

Application filed February 16, 1916. Serial No. 78,574.

To all whom it may concern:

Be it known that I, WILLIAM M. BARBER, of Somerville, in the county of Middlesex and State of Massachusetts, a citizen of the

United States, have invented a new and useful Improvement in Machines for Drying Paper, of which the following is a full, clear, and exact description, reference being had to the accompanying drawings, forming a part of this specification, in explaining its nature.

The present invention relates to a machine for drying all kinds of paper in the continuous web and especially sized paper, both envelope-sized and tub-sized.

The mechanical drying of paper in the continuous web, that is, by the application of artificial heat, presents difficulties which must be overcome in order to successfully accomplish the work. Owing to the continuous running of the web, the drying of the paper must be accomplished within a relatively limited time. The application of a high degree of heat, however, tends to

bake the paper and injure its fiber. On the other hand, if too light a heat be employed, the drying cannot be successfully accomplished within the allotted time. Owing to the difference in papers an application of

heat which would be effective in one case would be detrimental in another. For example, a very thin paper might allow of a continuous application of heat for drying it. The same application of heat, however, to a thicker paper and especially a sized paper would have the initial effect of drying the surfaces of the sheet and form as it were thin shells which would prevent the evaporation of moisture from the interior of the

sheet and accordingly the interior of the sheet would be left undried. With the thicker paper the heat must be so moderated that the sheet will be dried gradually and uniformly throughout. With some kinds of

paper, as for example paper to be calendered, it is desirable that a certain percentage of moisture be left in the sheet. In fact, with practically all paper great care should be exercised in the drying after the moisture is about gone, not to apply too high a

degree of heat as this would overdry the paper and leave it brittle and without life.

Another difficulty resides in the fact that as the sheet dries it contracts longitudinally and laterally. Such contraction must be compensated for at all times during the

drying. Unless compensated for the contraction might otherwise tend to stretch the paper and the bonded fiber would become disrupted.

It is my object to overcome all difficulties of the kind above indicated and other difficulties which might be referred to, and to provide a machine applicable for the drying of any kind of paper in the continuous web and especially sized papers which should be dried with great care.

My invention can perhaps best be seen and understood by reference to the drawings, in which an embodiment thereof is shown applied to that type of paper-drying machine which forms the subject matter of my United States Patent No. 690,629, dated January 7, 1902, only those parts being shown necessary for a proper understanding of the invention.

In the drawings:—

Figure 1 is a front elevation of the machine.

Fig. 2 is a rear elevation.

Fig. 3 is a forward end elevation.

Figs. 4 and 5 are sectional details of construction to which special reference will later be made, and

Fig. 6 is a perspective of a further detail of construction.

Referring to the drawings:—

The frame of the machine comprises lines of spaced posts or standards 1 rising along its front and rear sides. These posts are connected at the top and near the bottom along the front and rear sides of the machine by interposed frame sections 2 which run longitudinally of the machine and form the top and bottom side rails thereof. The interposed sections or side rails 2 are connected by the rods 3 which run laterally between the two sides of the machine.

From the above description it will be seen that the frame is of a sectional character and admits of any desired variation in the longitudinal extension of the machine as may be required.

The side rails 2 furnish supports for the rolls around which the web extends. Of these rolls 5 represents the top rolls or those that are supported by the top side rails of the machine, and 6 the bottom rolls supported by the bottom side rails. The rolls 5 are each mounted to turn within bearings formed by pillows or blocks 8 secured directly to the under sides of the top side rails,

while the bottom rolls 6 are each mounted to turn within a cradle 9 which is mounted to turn pivotally within pillows or blocks 10 secured to the upper sides of the bottom 5 side rails. Further attention will be directed at a later point to this special mounting of the bottom rolls.

11 represents the web of paper. The web passes successively over the top rolls and beneath the bottom rolls, forming a succession of narrow spaces or compartments opening successively upwardly and downwardly, all substantially as shown and described in my aforesaid patent. The web is moved by 15 power applied to the top rolls 5. Any of the known modes of power transmission may be employed in this connection, although it is desirable that power be applied to all the top rolls and some provision be made for varying the speed of the rolls in order to compensate for contraction in the web as is customary in devices of this kind.

Arranged at different points along the web are a series of air-distributing units 12 25 at each of which air may be applied to a separate and distinct portion of the web throughout its extension in the machine. These units take the form in the present instance of boxes adapted to hold air under 30 compression whereby it may emanate therefrom and be applied to the web. The boxes are arranged both along the top and along the under sides of the machine whereby the air issuing from them may enter the various 35 spaces or compartments between the folds of the web. Of these boxes those along the top of the machine above the web, extend laterally between the top side rails and rest thereon, being secured to the rails in 40 any suitable manner. The bottom line of boxes, or those arranged below the web, also extend laterally of the machine and are secured to depend from the bottom side rails, attachment being secured in any suitable 45 manner.

Each of the boxes is of sufficient size to contain a considerable volume of air, and it is also to be observed that their width is preferably such that each box may supply 50 air to two or more openings or compartments between the folds of the web to which the box is adjacent. Each of the top line of boxes is preferably provided with a bottom 55 13 having in it nozzles 14 directed into the several compartments between the folds of the web over which the box is arranged, the disposition of these nozzles also being such that the air issuing therefrom may be directed to flow against the sides of the web. 60 In the bottom line of boxes each box is provided with a perforated cover 15 through which the air issues into the several compartments beneath which the box is placed. Air-distributing nozzles are dispensed with 65 in the bottom boxes for the reason that hot

air is usually applied to the web and the tendency of this air is to rise and accordingly it does not require so much forcible distribution as that imparted by a nozzle.

Air under compression is supplied to the 70 various boxes from an air chest common to all the boxes and within which the air is compressed. This chest is indicated by the receptacle 16 running along the rear side of the machine and occupying preferably 75 an elevated position. This receptacle or chest may be supported in any suitable manner. Atmospheric air is introduced into and is compressed within the chest by a rotary fan 17 mounted within an opening 18 in 80 the wall of the chest. The fan operates in the usual manner. The air compressed within the chest is led into the various boxes by conduits, 19 representing those which connect with the upper or top line of boxes and 85 20 the conduits leading from the chest and connecting with the lower line of boxes.

Located within each of the air-distributing units are steam heating coils 21. The coils in the upper line of boxes rest upon 90 bars 22 laid in the bottoms of the boxes and are otherwise supported by the cross tie rods 3 which are arranged to extend beneath the bottoms of the boxes. The coils contained within the lower line of boxes rest upon 95 rods 23 supported by straps 24 from the tie rods 3 which connect the bottom side rails of the machine.

Steam is introduced into the various coils from steam pipes arranged outside the 100 respective lines of boxes and running along the front side of the machine, 26 representing the pipe supplying steam to the coils in the upper line of boxes and 27 the pipe supplying steam to the coils in the lower line of 105 boxes. The admission of steam to each of the coils from the main steam pipe with which the coil connects is controlled by means of a valve 28 located within the pipe connection. By means of these valves the 110 admission of steam to any of the coils may be entirely shut off or otherwise controlled as may be desired, with the resultant effect that the air issuing from any one box may be either cool air or that having the same 115 temperature as that introduced into the box from the chest, or it may be heated air having such variety of temperature as a full or partial admission of steam to the coil may permit. The steam coils are each provided 120 with such return pipes and traps for carrying off the water of condensation as may be required.

It will thus be seen that there is provided means whereby practically any desired variation may be obtained in the temperature of air applied to the different portions of the web. For example, steam may be shut off from the coils within the boxes adjacent the wet end of the machine and be admitted to 130

the coils in the boxes arranged along the middle of the machine and excluded from the coils in the boxes at the dry end of the machine, or any other variation may be practised as circumstances may require.

Reference has already been made to the fact that in a machine of this kind some provision must necessarily be made to compensate for the contraction of the web during the drying else the web becomes stretched and the bonding of the fiber weakened, destroying the strength of the paper. A very satisfactory compensation is customarily provided through a variance in the speed of the rolls carrying the web, or, in other words, those rolls to which the power is applied. In the present instance, however, I have provided further means which furnish a very valuable adjunct in permitting the contraction of the web, and I refer to the manner of supporting the lower set of rolls, that is, the idler rolls around which the web passes and to which power is not applied. As previously noted, these rolls turn within a cradle comprising, as may be seen in Figs. 1 and 6, a shaft or rod 30 journaled to turn within the pillows or blocks 10 fixed to the bottom side rails of the machine. Fixed to the ends of this rod just inside the bearings 30 in which the rods turn, are arms 31. These arms are parallel to one another and project outwardly. It is these arms of the respective cradles which support the bottom rolls 6, these rolls being interposed between the ends of the arms and turning within bearings 32 formed on the ends of the arms.

Thus mounted, the rolls may not only turn freely in their respective cradles, but are also supported to yield to contraction in the web by the turning of each cradle about its axis. The normal position of each of the rolls is one in substantially the same horizontal plane with the axis of the cradle with the roll supported by the bottom side rails of the frame. This effect is obtained by the resting of the bearings 32 upon the side rails. Under these circumstances each of the rolls will yield to the contraction of that portion or fold in the web passing around it when such contraction exerts sufficient stress upon the roll as to lift it, the roll then yielding by the pivoting of the cradle as above explained.

In order that the roll may yield before the lifting stress exerted by the web upon the roll due to contraction becomes such as to stretch the paper and disrupt the fiber, each roll is provided with a counterbalance. This counterbalance is obtained by extending the rod 30 of the cradle beyond the bearings within which the rod is mounted to turn at the rear of the machine and securing to the rod so extended an arm 34 upon which is arranged an adjustable weight 35, the arm extending in a direction substan-

tially reverse to that of the extension of the body of the cradle. By a proper adjustment of the weight upon the arm the weight may be brought to compensate for the weight of the roll and that portion of the cradle exerting resistance to the lifting and yielding of the roll by the contraction of the web, and the roll may be made to lift or yield when the contracting stress of the web upon the roll to lift it reaches a determinate amount. Of course some papers will bear very much more tension than others before disruption of the fiber is effected, all of which can be compensated for by the adjustment of the counterbalance to the particular paper.

There is of course a limit to which each of the rolls can yield, but before this limit is reached it will be understood of course that some other compensating means has effected a proper readjustment of the web when the roll or rolls which have yielded will be either returned to their normal position or to a position where they are capable of further yielding.

Not only does the cradling of the roll provide a very efficient means for permitting the contraction of the web, but owing to the rigidity of the cradle and its maintenance of the roll in perfect parallelism with the axial center about which the roll turns, there is insured proper centering of the web within the machine regardless of whether the web be a wide or a narrow web.

Having thus fully described my invention, I claim and desire to secure by Letters Patent of the United States:—

1. In a machine for drying paper in the continuous web, means for carrying the web, a series of air-distributing units arranged at different points along the web from which air under pressure may be applied to different portions of the web, means for supplying air to the various units, and means whereby the temperature of the air emanating from the several units may be controlled and variation be effected in the temperature of the air emanating from certain of said units in relation to the temperature of air emanating from other of said units as occasion may require.

2. In a machine for drying paper in the continuous web, means for carrying the web whereby it may form by folds therein separate compartments, means for introducing air into said compartments whereby it may be applied to different portions of the web, and means whereby the temperature of the air introduced into said compartments and applied to the web may be controlled and variation be effected in the temperature of the air applied to certain portions of the web in relation to that applied to other portions thereof as occasion may require.

3. In a machine for drying paper in the

continuous web, means for carrying the web whereby it may form by folds therein separate compartments, separate air-distributing units arranged at different points along 5 the web adjacent said compartments for introducing air severally thereto, means for supplying air to said units, and means whereby the temperature of the air emanating from said units and introduced into 10 said compartments may be controlled as to temperature and variation be effected in the temperature of air introduced into certain of said compartments in relation to that introduced into other of said compartments 15 as occasion may require.

4. In a machine for drying paper in the continuous web, means for carrying the web, a series of air-distributing boxes arranged adjacent said web at different points along 20 the same for applying air to different portions thereof, an air chest common to said boxes and connecting severally therewith, means for compressing air within said chest, means for heating the air within said boxes 25 whereby hot air may emanate therefrom against said web, and means for controlling such application of heat whereby variation may be obtained in the temperature of the air emanating from said boxes and applied 30 to different portions of the web.

5. In a machine for drying paper in the continuous web, means for carrying the web, a series of air-distributing boxes arranged adjacent said web at different points along 35 the same for applying air to different portions thereof, an air chest common to said boxes and connecting severally therewith, means for compressing air within said chest, steam pipes contained in each of said boxes, 40 and means for severally controlling the admission of steam to said pipes.

6. In a machine for drying paper in the continuous web, means for supporting the web whereby a fold may be formed therein 45 and comprising in part a roll located within said fold, a counterbalanced pivoted support carrying said roll and on which said roll turns, and means for pivotally mounting said support whereby the roll may yield to 50 contraction of the web by the pivotal turning of said support.

7. In a machine for drying paper in the continuous web, means for supporting the web whereby a fold may be formed therein 55 and comprising in part a roll located within the fold, a cradle bearing said roll and within which said roll is mounted to turn, means for pivotally mounting said cradle, and a counterbalancing means carried by said 60 cradle.

8. In a machine for drying paper in the

continuous web, separate sets of rolls over which the web passes to form a succession of folds, and means for yieldingly supporting each roll of one of said sets of rolls whereby 65 the rolls so yieldingly supported may yield to contraction in the successive folds of the web.

9. In a machine for drying paper in the continuous web, separate sets of rolls over 70 which the web passes to form a succession of folds, and means for yieldingly supporting each roll of one of said sets of rolls whereby the roll so yieldingly supported may yield to contraction in the successive folds of the 75 web, said means comprising a cradle or support in which the roll is mounted to turn, means for pivotally mounting said support and a counterbalancing device carried by the support. 80

10. In a machine for drying paper in the continuous web, means for supporting the web whereby a fold may be formed therein and comprising in part a roll located within the fold, a yielding carrier for said roll with- 85 in which the roll turns, a rest for said carrier against which said carrier normally bears, and means for counterbalancing said carrier and roll carried by it.

11. In a machine for drying paper in the 90 continuous web, means for supporting the web whereby a fold may be formed therein and comprising in part a roll located within the fold, a pivoted carrier for said roll on which the roll turns, said roll lying in a position offset from the axis of said carrier, and a rest for said carrier against which the carrier and roll carried by it normally bear. 95

12. In a machine for drying paper in the continuous web, the combination with the 100 frame of the machine, of separate sets of top and bottom rolls over which the web passes to form a succession of folds, a yielding carrier for each one of the set of bottom rolls, each carrier resting normally upon a portion 105 of said frame, and means for counterbalancing each of said carriers and roll carried by it.

13. In a machine for drying paper in the continuous web, the combination with the 110 frame of the machine, of separate sets of top and bottom rolls over which the web passes to form a succession of folds, a pivoted car- 115 rier for bearing each roll of the bottom set of rolls and within which carrier the roll turns in a position offset from the axial center of said carrier, said carrier and roll carried by it resting normally upon a portion of said frame, and means for counterbalancing each of said carriers and roll carried 120 by it.

WILLIAM M. BARBER.
